CLAIM

The ornamental design for an illuminated compact, substantially as shown and described.

DESCRIPTION

FIG. 1 is a front perspective view from above and one side of an illuminated compact in a closed position showing my new design;

FIG. 2 is a rear perspective view from below and the other side thereof;

FIG. 3 is an underneath plan view thereof; and

FIG. 4 is a perspective view of the illuminated compact of my new design similar to FIG. 1 but showing the compact in an open position.

FIG.1.

FIG.2.

FIG.3.

FIG. 4.
